US0D1063336S

(12) United States Design Patent (10) Patent No.: US D1,063,336 S
(45) Date of Patent:  *Feb. 25, 2025

(54) SHOE SOLE

(71) Applicant: Gavrieli Brands LLC, Beverly Hills, CA (US)

(72) Inventors: Kfir Gavrieli, Beverly Hills, CA (US); Dikla Gavrieli, Beverly Hills, CA (US)

(73) Assignee: Gavrieli Brands LLC, Beverly Hills, CA (US)

(*) Notice: This patent is subject to a terminal disclaimer.

() Term: 15 Years

(21) Appl. No.: 29/859,107

(22) Filed: Nov. 7, 2022

Related U.S. Application Data

(63) Continuation of application No. 29/759,290, filed on Nov. 20, 2020, now Pat. No. Des. 968,778, which is a continuation of application No. 17/001,360, filed on Aug. 24, 2020, now Pat. No. 11,825,906, which is a continuation of application No. 15/905,239, filed on Feb. 26, 2018, now abandoned, which is a continuation of application No. 15/204,763, filed on Jul. 7, 2016, now Pat. No. 9,930,925, and a continuation of application No. 14/266,599, filed on Apr. 30, 2014, now Pat. No. 9,398,786, which is a continuation of application No. 13/207,397, filed on Aug. 10, 2011, now Pat. No. 8,745,893.
